SPRAY GUN

Fred W. Wahlin, St. Charles, Ill., assignor to Spraying
Systems Co., a corporation of Illinois

Filed May 25, 1962, Ser. No. 70,282

Term of patent 14 years

(Cl. D62—2)

*Fig. 3.**Fig. 4.**Fig. 5.*FIG. 1 is a side perspective view of a spray gun showing my new design;

FIGS. 2 and 3 are top and bottom plan views respectively of the portion of the gun shown in full lines;

FIGS. 4 and 5 are side elevational views of that portion of the gun shown in FIGS. 2 and 3.

The dominant features of my design reside in the portions shown in full lines.

I claim:

The ornamental design for a spray gun, substantially as shown and described.
